UNITED STATES PATENT OFFICE.

HARRY TUNSTALL, OF FAIRHAVEN, MASSACHUSETTS, ASSIGNOR TO ALSATIAN MACHINE COMPANY, OF BOSTON, MASSACHUSETTS, A CORPORATION OF MASSACHUSETTS.

COMBING-MACHINE.

1,351,077.

Specification of Letters Patent. Patented Aug. 31, 1920.

Application filed October 29, 1919. Serial No. 334,226.

To all whom it may concern:

Be it known that I, HARRY TUNSTALL, a subject of George V, King of Great Britain and Ireland, residing at Fairhaven, in the 5 county of Bristol and State of Massachusetts, have invented a new and useful Improvement in Combing-Machines, of which the following is a specification.

Cotton fiber is short and very fine. In its 10 progress through a combing machine the lap passes over what is known as a cushion plate against which it is fed by a feed roll which rests on top of it, the cushion plate serving to support the under surface of the 15 lap and forming part of the nipper system. The cushion plate is made of metal and is presumably smooth, but minute projections exist on its upper surface which engage the fibers forming the under surface of the lap 20 and prevent the lap from being properly fed, causing the fibers on its under surface to drag and be looped or doubled and drawn out of parallel relation with their neighbors, so that more waste is produced 25 than is desirable.

The purpose of this invention is to overcome these faults as far as possible by providing the upper side of the cushion plate with a supporting surface which shall be 30 mathematically smooth, for this purpose being made of some fine grained metal or a metal which is so plated as to produce a glazed surface, that is, a surface which is practically as smooth as glass, or it may 35 be made of porcelain or the like. Anyone skilled in the art will appreciate that there are a number of materials which may be used for this purpose either by themselves or as a plating to a metal foundation. I 40 prefer to inlay the ordinary cushion plate with such a glazed plate.

My invention will be understood by reference to the drawings in which—

- Figure 1 is a plan of such glazed plate; 45 Fig. 2 a view taken at one end thereof. Fig. 3 is a plan of the cushion plate with a glazed plate attached thereto showing the position of the feed roll upon such plates, and 50 Fig. 4 is a cross section on line 4—4 of Fig. 3.

A is the glazed plate which may be of

any desired shape so long as it receives upon it the lap and leads it off to the hooked end b of the cushion plate B. The glazed 55 plate is attached to the cushion plate by screws a preferably near its rear edge. C is the feed roll and c is the lap which passes under the feed roll and over the cushion plate into position to be combed at 60 the proper time. The means of mounting the cushion plate and the feed roll are not shown as they are well known in the art. It will be noticed that by making the plate 65 of thin metal and attaching it near its rear edge its tendency will be to spring up against the roll and hold the lap in close contact with it.

I have used the term "glazed" to express a condition of microscopic smoothness,—one 70 not attained in ordinary construction without great expense both of material and labor.

What I claim as my invention is:—

1. In a combing machine, means for feeding the sliver comprising a feed roll and a cushion plate having a glazed upper surface adapted to cooperate with said feed roll to feed the fibers of the sliver whereby said fibers will be delivered by said feed 75 roll in the same relative relation to each other as that in which they are delivered to said feed roll and cushion plate.

2. In a combing machine, as a means for feeding the sliver, in combination, a cushion plate and a feed roll adapted to press the sliver against, and feed it over, said cushion plate, the feeding surface of said cushion plate being glazed in character, whereby the fibers will be discharged from said cushion 80 plate in the same relation to each other as when received upon it.

3. In a combing machine, as a means for feeding a sliver, a feed roll and a cushion plate having a thin glazed plate mounted 85 thereon, means for attaching said glazed plate to said cushion plate near the rear edge thereof whereby the front edge of said glazed plate will tend to spring up against said feed roll and hold the sliver in close 90 contact therewith and said sliver will be fed freely and without deformation of its fibers by said feed roll.

HARRY TUNSTALL.
